(57) **CLAIM**

The ornamental design for a favored angle screw, substantially as shown and described.

DESCRIPTION

FIG. 1 is an exploded perspective view of the favored angle screw comprised of a set screw, spinal rod, rod conforming screw, threaded screw element and coupling element showing our new design;

FIG. 2 is an enlarged, partial perspective view of the favored angle screw of FIG. 1, fully assembled and coupled to the spinal rod;

FIG. 3 is a side view thereof, showing the threaded screw element in an alternate position with the spinal rod removed for ease of illustration;

FIG. 4 is a second side view thereof, showing the threaded screw element in a second alternate position with the spinal rod removed for ease of illustration;

FIG. 5 is a perspective view of a coupling element of the favored angle screw of FIG. 1;

FIG. 6 is a top view of the coupling element of FIG. 5;

FIG. 7 is a front view of the coupling element of FIG. 5; and,

FIG. 8 is a side view of the coupling element of FIG. 5.
